(57) **CLAIM**

We claim the ornamental design for a cocktail plate, as shown and described.

DESCRIPTION

FIG. 1 is a perspective view of a cocktail plate showing our new design;

FIG. 2 is a front elevational view thereof;

FIG. 3 is a rear elevational view thereof;

FIG. 4 is a side elevational view of the right side thereof, the side elevational view of the left side being a mirror image of the right side elevational view;

FIG. 5 is a top plan view thereof; and,

FIG. 6 is a bottom plan view thereof.
